(57) **CLAIM**

The ornamental design for a table base, as shown and
described.

DESCRIPTION

FIG. 1 is an isometric view of a table base in accordance with
the new design;

FIG. 2 is a front elevational view thereof;

FIG. 3 is a right side elevational view thereof;

FIG. 4 is a left side elevational view thereof;

FIG. 5 is a rear elevational view thereof; and,

FIG. 6 is a top view thereof.

The broken lines in the figures are for illustrative purposes
only and form no part of the claimed design.
